United States Patent Office

Des. 195,509
Patented June 25, 1963

195,509

ELECTRONIC CABINET

Robert Van Valkinburgh, Montgomery County, Pa., assignor to Sperry Rand Corporation, New York, N.Y., a corporation of Delaware

Filed Oct. 18, 1962, Ser. No. 72,186

Term of patent 7 years

(Cl. D26—5)

FIG. 1

FIG. 2

FIG. 1 is a front perspective view of an electronic cabinet, showing my new design; and

FIG. 2 is a rear perspective view thereof. The rear of the control panel as shown in FIG. 2 is provided with screening, the outline of which is illustrated in the drawing.

I claim:

The ornamental design for an electronic cabinet, as shown and described.
